(57) **CLAIM**

We claim the ornamental design for a lifting cylinder, as shown.

DESCRIPTION

FIG. 1 is a front view of a lifting cylinder, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines shown in the figures are for the purpose of illustrating portions of the lifting cylinder and form no part of the claimed design.

1 Claim, 7 Drawing Sheets
